EXERCISING DEVICE

Anthony F. Sak, Bernardston, Mass.

Application April 2, 1941, Serial No. 386,436

8 Claims. (Cl. 272—72)

This invention is directed to improvements in exercising devices, and is particularly pertinent to that class of exercising device which is generally known as rowing apparatus.

An object of this invention is to provide an exercising device having the general characteristics of a rowing machine, which is extremely simple and economical of manufacture, sturdy in construction, and capable of efficient service for an indefinite period without maintenance or service, such as lubrication, repairs, or replacement of parts.

A further object of this invention is to provide an exercising device of the character described which includes an operating handle and means for providing resistance to movement of the operating handle in either direction from its neutral or median position.

A still further object of this invention is to provide a device of the character described including means for adjusting the initial or neutral angle of the operating handle, whereby the arc of movement may be adjustably determined to suit the operator.

Another object of this invention is to provide, in a device of the character described, a handle bar and means for adjustably positioning the handle bar to vary the length of the stroke, and to adapt the device to the length of the arms of the operator.

Again, an object of this invention is to provide a simple, light weight structure of the character described which may be folded or collapsed into a compact, flat package for transportation, packing, or storage.

These, and other objects and advantages of this invention will be completely and concisely disclosed and described in the following specification, the accompanying drawings, and the appended claims.

Broadly, this invention comprises a frame, a seat secured on one end of the frame, a handle pivotally secured adjacent the opposite end of the frame, a cylinder pivotally supported on the frame near the seat end, a piston slidably supported in the cylinder, compression springs in the cylinder engaging both sides of the piston, a connecting rod secured to the piston and pivotally connected to the handle, means for adjustably positioning the pivotal connection of the connecting rod and handle, a handle bar, and means for adjustably positioning the handle bar in the handle relative to the pivotal connection of the handle on the frame.

A preferred embodiment of this invention is

illustrated in the accompanying drawings, in which—

Fig. 1 is a perspective view of the exercising device,

Fig. 2 is a cross section through the handle, Fig. 3 is an underside plan view of one of the end or cross bars,

Fig. 4 is a perspective view of the front cross bar or foot brace,

Fig. 5 is a cross section illustrating the removable pivot pin and piston connecting rod, taken on the line 5—5 of Fig. 6,

Fig. 6 is a longitudinal sectional view of the exercising device,

Fig. 7 is a cross section taken on the line 7—7 of Fig. 6, and

Fig. 8 is a cross section of the cylinder, taken on the line 8—8 of Fig. 6.

Referring now to the drawings in detail, in which like numerals refer to like parts throughout,

A pair of frame members 1 are bolted or otherwise secured at front and rear ends to cross bars 2 and 3, respectively, in parallel, spaced relation, as best indicated in Figs. 1 and 7. Foot pads 4, of rubber or other suitable resilient material, are secured on the under side of the cross bars 3 and 4 in angular or "toenailed" relation, thereby providing resistance against both longitudinal and transverse movement of the device when it is placed on a floor or other supporting surface. The front cross bar 2 is chamfered on either side of the frame members 1, as indicated at 5, to provide angular surfaces against which the feet of an operator of the device may be braced. A seat 6 is secured on the upper surfaces of the frame members 1, over the rear cross bar 3.

A handle 8 is pivotally secured between the frame members 1, adjacent their front ends, by means of a pivot pin 9. A handle bar 10 is slidably and removably supported in one of a plurality of holes 11 formed in the upper portion of the handle 8. The diameter of the grip portions 12 of the handle bar 10 is small enough to permit withdrawal of the handle bar 10 from the holes 11, as best indicated in Fig. 2.

A cylinder 13 is pivotally supported between and near the rear ends of the frame members 1 by means of a pivot pin or stud 14. A piston 15, provided with a connecting rod 16, is normally positioned midway in the cylinder 13, as indicated in Fig. 6, and compression springs 17 and 18 are supported in the cylinder 13 on either side of the piston 15. The spring 17 bears against the stud 14 and the piston 15, and the spring 18

bears against the opposite face of the piston 15 and a screw cap 19 removably secured over the front end of the cylinder 13. The springs 17 and 18 are enclosed in sleeves 20 of resilient, absorbent material such as cloth fabric, or the like, which may be soaked in a lubricant, either liquid or semi-solid, as oil or grease. The front end of the connecting rod 16 is provided with a head 21 which extends into a slot 22 formed in the handle 8, and is pivotally connected to the handle 8 by means of a pivot pin 23 engaged in one of a series of spaced holes 24 formed in the handle 8.

The device may be operated by a person seated on the seat 6 and grasping, with the hands, the handle bar 10. As the handle 8 is pulled toward the body, resistance is offered by the spring 17, and this resistance increases with the distance through which the handle is moved from its neutral position. When the handle 8 is pushed away from the body, resistance is offered by the spring 18, which acts in the same manner as the spring 17, but in reverse direction. Thus, effort is required to move the handle in either direction from its neutral position. No effort is required in returning the handle to neutral position, as the reaction of the springs 17 and 18 control these movements.

Adjustment of the length of swing of the handle 8 is controlled by adjustably locating the handle bar 10, and the neutral angle, or starting position, of the handle 8 is controlled by adjustably positioning of the pivot pin 23 in the holes 24.

With the pivot pin 23 and handle bar 10 removed from the handle 8, the cylinder 13 and its connecting rod 16, and the handle 8 may be lowered to rest between the frame members 1, as indicated by dash lines in Fig. 6, thereby providing a flat, compact package for storage, packing, and transportation.

If desired, a cap 25 may be secured on the lower end of the cylinder 13, and the cylinder packed with grease or other suitable lubricant.

Preferably, the members 1, 2, 3, 6, 8, and 10 are made of wood, or of a material having an equal or less specific gravity with wood, thereby providing an extremely lightweight apparatus which may be easily lifted or carried. Such a construction also results in economies in transportation and distribution.

What I claim is:

1. An exercising device comprising a pair of spaced, parallel frame members, a seat supported on said members at one end thereof, a handle pivotally supported between said frame members adjacent the opposite end thereof, a cylinder pivotally supported between said frame members beneath said seat, a piston in said cylinder, opposed compression springs in said cylinder on either side of said piston and acting on said piston, said piston being provided with a connecting rod which is pivotally secured on said handle.

2. An exercising device comprising a longitudinal rail, a seat secured on one end of said rail, a handle pivotally supported adjacent the opposite end of said rail, a cylinder pivotally supported on said rail adjacent the seat end, a piston in said cylinder, a connecting rod on said piston which is pivotally connected on said handle, and compression springs in said cylinder on either side of said piston and bearing against said piston.

3. An exercising device comprising a pair of spaced, parallel frame rails, said rails being

5 secured on and supported by cross bars at each end, angularly disposed resilient foot pads secured on the under side of said cross bars, a seat secured on the top surface of said rails at the rear end thereof, a handle pivotally secured on and between said rails adjacent the front ends thereof, a cylinder having its rear end pivotally supported between said rails adjacent the rear ends of said rails, a piston normally positioned midway in said cylinder, a connecting rod on said piston and pivotally connected on said handle, and compression springs in said cylinder on either side of said piston and bearing against said piston.

4. An exercising device comprising a stationary frame, a seat on said frame, a handle pivotally supported on said frame at a point remote from said seat, a cylinder pivotally supported on said frame adjacent said seat, a piston in said cylinder, a connecting rod on said piston and pivotally connected to said handle, and a compression spring in said cylinder acting upon said piston to resist movement of said handle toward said seat.

5. An exercising device comprising a stationary frame, a seat on said frame, a handle pivotally supported on said frame at a point remote from said seat, a cylinder pivotally supported on said frame adjacent said seat, a piston in said cylinder, a connecting rod on said piston and pivotally connected to said handle, and a compression spring in said cylinder acting upon said piston to resist movement of said handle away from said seat.

6. An exercising device comprising a stationary frame, a seat on said frame, a handle pivotally supported on said frame at a point remote from said seat, a cylinder pivotally supported on said frame adjacent said seat, a piston in said cylinder, a connecting rod on said piston and pivotally connected to said handle, compression springs in said cylinder on either side of said piston and acting upon said piston to resist movement of said handle either toward or away from said seat.

7. An exercising device comprising a frame, a seat secured on one end of said frame, a handle pivotally secured on the frame remote from said seat, a cylinder pivotally supported on said frame near the seat end, a piston slidably supported in said cylinder, compression springs in said cylinder engaging opposite faces of said piston, a connecting rod on said piston and pivotally connected to said handle, means for adjustably positioning the pivotal connection of said rod on said handle relative to the pivotal support of said handle.

8. An exercising device comprising a frame, a seat secured on one end of said frame, a handle pivotally secured on said frame remote from said seat, a cylinder pivotally supported on said frame near the seat end, a piston slidably supported in said cylinder, compression springs in said cylinder engaging opposite faces of said piston, a connecting rod on said piston and pivotally connected to said handle, said springs being enclosed in resilient, oil-absorbent fabric sleeves, means for adjustably positioning the pivotal connection of said rod on said handle relative to the pivotal support of said handle, a handle bar, and means for adjustably positioning said handle bar in said handle relative to the pivotal support of said handle.
